(57) **CLAIM**

The ornamental design for a sushi holder, as shown and described.

DESCRIPTION

FIG. 1 is a front, right and top perspective view of a sushi holder, showing my new design;

FIG. 2 is a front elevation view thereof;

FIG. 3 is a rear elevational view thereof;

FIG. 4 is a left side elevational view thereof, the right side elevational view being a mirror image of the left side elevational view; and,

FIG. 5 is a top plan view thereof.
